UNITED STATES PATENT OFFICE.

SAMUEL B. COSTEN, OF SCRANTON, PENNSYLVANIA, ASSIGNOR TO H. H. COSTON AND W. D. COSTON, BOTH OF SAME PLACE.

RACK OR STAND FOR HOLDING MANUSCRIPT OR OTHER MATTER TO BE COPIED.

SPECIFICATION forming part of Letters Patent No. 354,045, dated December 7, 1886.

Application filed April 19, 1886. Serial No. 199,378. (No model.)

To all whom it may concern:

Be it known that I, SAMUEL B. COSTEN, a citizen of the United States, residing at Scranton, Lackawanna county, Pennsylvania, have 5 invented an Improved Rack or Stand for Holding Manuscript or other Matter to be Copied, of which the following is a specification.

The object of my invention is to provide a convenient and readily - adjustable rack or 10 stand adapted to contain books, manuscript, or other printed or written matter which is to be copied by hand or on a writing-machine, or to be composed in type; and the broad idea of my invention is the provision of a suitable 15 standard, bracket, or other support adapted to sustain a glass-covered containing device or receptacle for the manuscript or book, which receptacle is arranged to be inclined, rotated, and adjusted at will, and contains a 20 spring-controlled movable back board or fol- lower adapted to press the matter to be copied, be its thickness what it may, forward against the glass or other transparent medium covering the case and retain it there in a fixed po- 25 sition.

In order to manufacture a stand of the fore- going general character in a convenient and simple manner, I have devised a construction of a character represented in the accompany- 30 ing drawings, and described in this specifica- tion.

The particular subject-matter which I claim as novel is hereinafter definitely specified.

In the drawings, Figure 1 is a front eleva- 35 tion of a frame embodying my invention. Fig. 2 is a side elevation of the same. Fig. 3 is a front elevation of the case with the cover removed and with the follower indicated in dotted lines. Fig. 4 is a side elevational de- 40 tail to the scale of Fig. 3, the case being in section in the plane of the dotted line $x-x$ of said Fig. 3. Fig. 5 is a transverse vertical sectional elevation through the cups G and H. Fig. 6 is a perspective view of the cup H. 45 Fig. 7 is a top plan view of the camway F.

Similar letters of reference indicate corre- sponding parts.

In the drawings, A represents a standard, pedestal, or other supporting device, which 50 may be of any convenient construction, ex- tends or otherwise, and which is adapted to

support the adjustable containing rack or case. The rack itself conveniently consists of a light metallic case or frame, B, conveniently made of wire, which is of depth sufficient to contain a 55 book, manuscript, or other copy - matter of any ordinary thickness.

The case is represented as conveniently made of an edge rail, b, of wire, which is conveniently supported upon curved bands or 60 straps b' of sheet metal, and is provided with a central band, b², through the medium of which the case as a whole is secured to the pedestal, preferably in a manner hereinafter 65 described.

C is a hinged cover containing glass c or other transparent medium. The hinges C se- 70 cure the cover to the case, and a spring catch, c², applied opposite to the hinges, holds the cover down in place upon the case and copy- 75 matter.

Within the case is placed a movable back board, which I for convenience term the "follower" D, which is cheaply made, of the skeleton form represented in Fig. 1, and which 75 conveniently rests upon springs E, conven- iently fastened in cups b', formed in or applied to the back or curved bands of the case. The follower, as mounted upon the springs, is adapted to form a backing to retain the book, 80 manuscript, or matter to be copied or read, be its thickness what it may, against the glass cover, and at the same time leave such matter clearly open to the sight.

The construction of the case, its cover, and 85 the follower may, if desired, be modified—and I have simply described and represented con- venient constructions—for it is evidently im- material whether the case be made as a wire skeleton or as a closed device, or whether the 90 follower be made in one, two, or more parts, or be supported upon spiral, elliptic, or other springs, or upon rubber or other compressible cushions.

It being important to apply the case, as a 95 whole, adjustably, both as to its inclination, as to its vertical set, and as to its capability for rotation upon the standard, I resort to the fol- lowing as a cheap and convenient mode of ap- 100 plication: The standard A is conveniently telescopic, so as to permit of vertical extension, and at its upper extremity it is provided with

a circular rotatable vertical-walled camway, F. To the back of the central band, b^2 , of the case is secured a cup, G, within which is telescopically fitted an inverted cup, H, which is hinged at h to the stem I, adapted to be entered for both longitudinal and rotary movement within the hollow standard. Interposed within the telescopically-related cups G and H is a compressed spiral spring, J, the respective ends of which spring are connected with the cups, and the operation of which is to draw the two cups telescopically together. The inverted cup H is provided with a circumferential slot, h' , provided with notches h^2 , and from the inner face of the cup G projects a stud, g, which is entered within said slot h' . By this means the two cups are connected, so that the cup G, which carries the case or frame, can be rotated with respect to the cup H, which is connected by the stem I with the standard, such rotation being possible by virtue of the stud, notched slot, and spring, by drawing the cups apart and so expanding the spring, in a manner which will be obvious to any mechanician. The result of the foregoing device is that the case, as an entirety, can be rotated with respect to the standard and disposed either in the position represented in the drawings or in another position in which its longer side stands vertically. The entire case can, by reason of its stem and the cups G and H, be rotated with respect to the standard, and by the rotation of the camway beneath the cup G. The case, with the work to be copied, can be inclined to any desirable angle to suit the light or sight of the copyist. Instead of employing the horizontal camway, it is obvious that the camway may be arranged vertically and operate direct against the back of the case, and also obvious that the telescopic cups may be of other forms or be replaced by any convenient pivoting device to permit of the rotation of the case.

K is a gage or liner, being a straight strip, a strip slotted longitudinally, a bent wire, or other similar device, which is suspended by a flexible spring-tape or other cord or strap, k, over the glass of the cover of the case. As this liner is intended to indicate the line to be copied, it is important that it should be capable of being moved up and down with respect to the cover and readily and quickly drawn out of the way when not in use. This is accomplished by winding the flexible spring-tape on a suitable pulley or similar device—such, for instance, as the spring-controlled pulley k^2 , contained in a removable case, k^3 . The shaft of the pulley k^3 is preferably provided either inside or outside with a ratchet-wheel, k^4 , which is controlled by a spring-pawl, k^5 , applied

to the case k^2 . This entire contrivance is one of convenience, and it may be omitted; or, if desired, the means of supporting the gage by a band adapted to be wound on a pulley may be modified, and the gage be supported at the sides of the case or frame B in such manner as convenience of manufacture may dictate.

Having thus described my invention, I claim and desire to secure by Letters Patent—

1. The combination of the rotatable case, the transparent cover thereof, and the spring-supported movable follower or back board in said case, substantially as described. 7c

2. The combination of the rotatable case, the transparent cover thereof, the spring-supported movable follower or back board in said case, the rotatable camway, and the standard, pedestal, or support, substantially as described. 75

3. The combination of the rotatable case containing the spring-supported follower and provided with the transparent cover, the support, and means for so connecting the case to the support that the case can be adjusted vertically or inclined, substantially as set forth. 80

4. The combination of the rotatable case, the transparent cover, the follower, the springs for controlling the action of the follower, and the rotating camway, substantially as set forth. 85

5. The combination of the case provided with the fixed cup, the inverted cup, the spiral spring connecting said cups, the rotatable stem, and the standard, substantially as described. 90

6. The combination of the standard provided with the camway, the case, the telescopic cup, and the stem, substantially as described. 95

7. The combination of the case, the stem hinged thereto, the hollow standard, and the camway mounted upon said standard, substantially as described. 100

8. In combination with the case provided with the transparent cover, the gage or liner, and means for adjusting the set of said gage or liner, substantially as and for the purposes specified. 105

9. The combination of the case provided with the transparent cover, the spring-controlled follower, the gage or liner, the support, and means for securing both the vertical adjustment of said case with respect to said support and its inclination with respect thereto, substantially as set forth. 110

In testimony whereof I have hereunto signed my name this 4th day of May, A. D. 1885.

SAMUEL B. COSTEN.

In presence of—

JOSEPH O'BRIEN,
FRANK E. RYAN.
